US00D927956S

(12) **United States Design Patent** (10) Patent No.: **US D927,956 S**
Tavernier (45) Date of Patent: **** Aug. 17, 2021**

(54) HANGER AND SUPPORT SET

(71) Applicant: **WE Group Europe**, Beaurepaire (FR)

(72) Inventor: **Eric Marie Thibaut Tavernier**, Lyons
(FR)

(73) Assignee: **WE Group Europe**, Beaurepaire (FR)

(**) Term: 15 Years

(21) Appl. No.: 29/689,947

(22) Filed: **May 3, 2019**

(51) LOC (13) Cl. 08-07

(52) U.S. Cl.

USPC **D8/330**; D8/71; D8/394

(58) **Field of Classification Search**
